United States Patent Office

Des. 196,049
Patented Aug. 20, 1963

196,049

PAPER TAPE UNIT

Robert H. Eytel, Blue Bell, Pa., assignor to Sperry Rand Corporation, New York, N.Y., a corporation of Delaware

Filed Sept. 17, 1962, Ser. No. 71,710

Term of patent 7 years

(Cl. D26—5)

FIG. 1

Des. 196,049

PAGE 2

FIG. 3

FIG. 1 is a left front perspective view of a paper tape unit, showing the new design;

FIG. 2 is a right rear perspective view of the paper tape unit; and

FIG. 3 is a top view thereof.

I claim:

The ornamental design for a paper tape unit, as shown.
